UNITED STATES PATENT OFFICE.

WILLIAM C. LINEAWEAVER, OF FORT SILL, OKLAHOMA, ASSIGNOR OF ONE-HALF TO
WORTHINGTON SWIFT, OF LAWTON, OKLAHOMA.

PLOTTER.

1,417,753.

Specification of Letters Patent. Patented May 30, 1922.

Application filed June 4, 1921. Serial No. 475,058.

To all whom it may concern:

Be it known that I, WILLIAM C. LINEAWEAVER, a citizen of the United States, residing at Fort Sill, in the county of Comanche and State of Oklahoma, have invented certain new and useful Improvements in Plotters, of which the following is a specification, reference being had therein to the accompanying drawings.

10 This invention relates to plotters and has for an object to provide an instrument embodying new and improved features of convenience, accuracy and expedition.

A further object of the invention is to 15 provide a rectangular and preferably square frame work having a cross bar perpendicular to the connecting sides and rigidly, but separably, secured thereto with a rule sliding relative to said cross bar, with 20 means for maintaining said slide rule in perpendicular relation to said cross bar.

With these and other objects in view the invention comprises certain novel parts, units, elements, combinations, functions and 25 mechanical movements, as disclosed in the drawing, together with mechanical equivalents thereof, as will be hereinafter more fully described and claimed.

In the drawings:

30 Figure 1 is a view of the plotter in top plan superposed upon a sheet on which plotting is being carried out;

Figure 2 is a top plan view of the plotter with parts broken away showing the elements in enlarged relation;

Figure 3 is a sectional view through the plotter on line 3—3 of Figure 2, and

Figure 4 is an enlarged perspective view of one end of the sliding rule and the sliding 40 connection with the side frame.

Like characters of reference indicate corresponding parts throughout the several views.

The improved plotter which forms the 45 subject matter of this application comprises a rectangular and preferably square frame composed of side bars 10 and 11 and perpendicular bars 12 and 13, the latter bars being grooved, as indicated at 14.

50 To the side bars 10 and 11 a cross bar 15 is rigidly, but removably, secured by means of bolts and thumb nuts 16. The cross bar 15 is provided with a rib 17 and a rule, indicated as an entirety at 18, slides relative 55 to the cross bar 15 and side bars 12 and 13.

The rule 18 is made up of sections, as in-

dicated more particularly at Figure 3, and where the bar 15 is crossed, a keeper 19 is employed rigidly but removably secured to the sections of the rule by means of screws 60 and thumb nuts 20.

The sliding connection of the rule 18 with the side bars 12 and 13 consists of a block 21 at each end, rigidly but removably secured thereto by bolts and thumb nuts 22, 65 having a tongue 23 slidable in the grooves 14 in the bars 12 and 13.

The frame is made rigid in any usual and ordinary manner, as by means of the braces 24, so that the rule 18 will move longitudinally of the bar 15 conveniently without binding and by reason of the engagement of the parts will be maintained in perpendicularity with said bar 15.

With the device disposed upon a sheet, as 75 shown at Figure 1, it is obvious that plotting may be carried out by moving the rule 18 relative to the bar 15 and consequently to the work indicated at 25, and by moving the entire organization relative to the sheet 80 or the sheet relative to the organization, the bar 15 may be brought into such relation to the sheet as may be desired in conjunction with the sliding rule 18.

While it would be possible to point out 85 here a result which might come from the use of such an organization and the exact manner of using it, it will be obvious that there will be a great number of uses for such a device and that any explanation of the 90 manner of use would be superfluous and would be directed to only a single function or a single means from a multitude of possibilities and without adding to the understanding of the structure as such.

95 What I claim to be new is:

1. A plotter comprising a rigid frame, a bar extending across the frame and rigidly secured to opposite members of the frame, and a rule slideable along and relative to the 100 bar and to the frame sections in parallelism with the bar.

2. A plotter comprising a rigid frame, a bar extending across the frame in parallelism with some of the frame members and 105 perpendicular to other of the frame members, a rule slideable upon the bar and perpendicular thereto and to some of the frame members, and means to maintain the perpendicularity of said sliding rule relative 110 to said bar and frame members.

3. A plotter comprising a rigid frame, a

bar extending across the frame and rigidly secured thereto by removable attaching members, some of the frame members being provided with slots in their proximate edges, a rule slideable relative to the bar and provided with detachable extremities accommodated and sliding in the said slots, and means carried by the sliding rule to maintain its perpendicularity to the bar.

10 4. A plotter comprising a rigid frame, a bar extending across the frame and rigidly and removably attached to opposite frame members and in perpendicularity thereto,

others of said frame members being provided with slots in their proximate sides, a rule composed of sections depressed upon opposite sides of the bar and having extremities sliding in the slots, and a member spanning the bar and rigidly attached to the rule sections. 20

In testimony whereof I hereunto affix my signature in presence of two witnesses.

WILLIAM C. LINEAWEAVER.
